UNITED STATES PATENT OFFICE

KENNETH J. TOBIN AND WILLIAM W. DARROW, OF CHICAGO, ILLINOIS, ASSIGNEES TO
CAMEL COMPANY, OF CHICAGO, ILLINOIS, A CORPORATION OF ILLINOIS

CORNER DOOR CONSTRUCTION

Application filed September 27, 1928. Serial No. 308,851.

This invention relates to a corner end door construction.

It is an object of this invention to provide an end door which embodies the corner of the car, whereby the largest possible diagonal entrance to the car is provided, and whereby the necessary swinging distance between coupled cars is shortened. This construction reduces the width of the side door so that the superstructure upon the side of the car need not be necessarily weakened.

The invention comprises the novel structure and combination of parts hereinafter described and more particularly pointed out and defined in the appended claims.

In the accompanying drawings which illustrate a preferred form of this invention and in which similar reference numerals refer to similar features in the different views:

Figure 1 is a fragmentary rear end elevational view of a house car with a rear door involving this invention.

Figure 2 is a fragmentary side elevational view of the car.

Figure 3 is a sectional view upon the line III—III of Figure 1.

Figure 4 is a view similar to Figure 3 illustrating the door in open position.

Referring to the drawings, there is shown a rear door 1 which is sufficiently narrow so that it can be readily swung to open position between a pair of coupled cars as shown in Figure 4. This door is hinged to the rear wall of the car by the hinges 2, and it extends in a right angle around the corner of the car. It will be noted that at the corner, the floor is provided with a post 3, and beyond the post 3 there is a side section 1a terminating in a post 4 which closes a part 40 of the side of the car. The post 4 has a Z bar 5 attached thereto with which a yielding metal strip 6 attached to the side of the post cooperates for forming a groove or lodgement for receiving the front edge of a sliding side door 7. The rear door is preferably covered with a metal sheet or panel 8 that is curved over the corner post 3 and also covers the section 1a.

Upon the rear section of the door 1 there is a casting 9 to which there is pivotally con-

nected a casting 10 secured to a swingable latching bar 11 the upper and lower ends of which are provided with castings 12 having flanges or lips 13. Oppositely facing keepers 14 and 15 are secured to the car above and below the latching bar for receiving the ends thereof. These keepers have flaring walls 14a and 15a so that as the ends of the latching bar engages thereunder the door will be drawn inwardly into tightly closed position. These flaring walls have overhanging lips or flanges 14b and 15b under which the lips 13 on the casting 12 are located when the bar is in latching position so that the upper and lower parts of the car will be tied together.

The aforementioned sliding side door 7 is provided with a hasp 16 that engages an apertured lug 17 on a casting 18 secured to the side section 1a. A pin 19 serves to secure the hasp upon said lug, whereby the latching mechanism of the sliding door secures the hinged door in closed position.

It will be appreciated that this corner car construction will maintain the rigidity of the car in service without naturally weakening the same, and at the same time it will provide a sufficient opening for speedily loading most any commodities.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. In a corner door construction for house cars, a door hinged to the rear of the car and comprising a rear section and a side section at right angles to the rear section, a post between said sections, said side section having a lodgement and a sliding side door having a front edge adapted for entering said lodgement.

2. In a corner door construction for house cars, a door hinged to the rear wall of the car and comprising a rear section terminating in a corner post and a side section extending from said corner post and a sheet metal

panel covering said rear section and bent around said post and covering said side section.

3. In a corner door construction for house cars, a door hinged to the rear wall of the car and having a right angled terminal provided with a lodgement, in combination with a sliding side door having a front edge adapted for entering said lodgement, and a 10 swinging latching bar upon said hinged door for maintaining the same in cooperation with the side door.

4. In a corner door construction for house cars, a rear door hinged to the rear wall of 15 the car and comprising a rear section and a side section extending from said rear section, and a sheet metal panel extending over said rear section and bent to also extend over said side section, and a swingable latching bar 20 for latching said door in tightly closed position.

5. In a corner door construction for house cars, a rear door hinged to the rear wall of the car and comprising a rear section and a 25 side section, said side section having a lodgement, a sliding side door having a front edge adapted for entering said lodgement and means for locking said side door to said rear door.

30 In testimony whereof we have hereunto subscribed our names at Chicago, Cook County, Illinois.

KENNETH J. TOBIN.

WILLIAM W. DARROW.
